UNITED STATES PATENT OFFICE

ETTA GRAY, OF NEW HAVEN, CONNECTICUT, ASSIGNOR TO BARCLEY CORSET COMPANY,
A CORPORATION OF NEW JERSEY

CORSETIERE'S FITTING APPARATUS

Application filed June 29, 1928. Serial No. 289,114.

One object of my invention is to provide apparatus for enabling corsetieres to modify the figure of the person for whom a corset is to be made, as it is desired that a corset shall do, and thereafter permit the corsetiere to take measurements from which an accurately fitting and satisfactory corset can be manufactured.

As is known to those skilled in the art a 10 corset as distinguished from other garments is worn primarily to change or modify the figure of the wearer, or to provide a certain degree of support or support at certain points. Therefore it is desirable that the 15 measurements taken from the figure be accurate and exactly according to the measurements of the figure as modified. Before my invention it was customary for a corsetiere to apply the old corset to the customer and 20 take the measurements from that, but frequently the old corset was not of the proper construction or was too nearly worn out, and measurements taken were accordingly erroneous and led to the making of unsatisfactory 25 corsets.

Other objects of my invention are to provide apparatus of the character described comprising a plurality of series of sections, the sections of each series being of different 30 sizes and each section having means for separably connecting it to another section, whereby a section from each of said series can be connected together according to the girth of the person to be fitted and applied to such 35 person to modify the figure as it is desired that a corset shall do; to provide such apparatus wherein each of said sections is composed of a plurality of relatively adjustable parts, and to obtain other advantages and 40 results as will be brought out by the following description.

Referring to the accompanying drawing in which corresponding and like parts are designated throughout the several views by 45 the same reference characters,

Figure 1 is a perspective view showing the front and back of an apparatus embodying my invention applied to a figure.

Figure 2 is a plan view of the apparatus 50 spread out its full length.

Figure 3 is a plan view of a front section of different size from that shown in Figure 2.

Figures 4 and 5 are similar views of different back sections, and

Figure 6 is a view similar to Figure 2 showing a modification of the front and back sections. 55

Specifically describing the invention the apparatus consists of a series of front sections of any suitable number, for example 60 three, two of which are designated in Figures 2 and 3 by the reference characters 1 and 2 respectively. The apparatus also includes a similar series of back sections which are designated in Figures 2, 4 and 5 as 3, 4 and 5 65 respectively. These sections of each series are of different sizes as will be evident from the respective figures of the drawing; and in the larger sizes, each section consists of a plurality of parts 6 which are connected together for relative adjustment by any suitable means such as the lacings 7. These front sections and back sections are complementary with side sections 8 which also preferably 70 comprise two parts 9 relatively adjustably connected by lacings 10. The side edges of all of the sections are provided with quick detachable or cast-off means such as separable fastener elements for connecting each section to a complementary section, for example, in 75 the present instance each edge of each front section is provided with a series of eyelets 11, while one edge of each side section 8 is provided with hooks 12 to connect with the eyes 11. The other edge of each side section 8 is 80 provided with hooks 13 with which cooperate eyes 14 on the edges of the back sections. The side sections are preferably formed with elastic gores 15. 85

In using the apparatus, one front section, one back section, and the two side sections are connected together by the hooks and eyes 11, 12, and 13, 14 as shown in Figure 2 in the drawings, and applied girthwise to the body of the person to be fitted for a corset. The particular size of front section or back section will be determined by the size of the person, a small person requiring the smaller sections, while a larger person requires the larger sections. The apparatus 90 95 100

is applied by connecting the fastener elements of the edges of the end sections, whichever may be the end sections; in the present instance eyes 14 on the one edge of the back section 3 will be connected to the hooks 13 on the edge of the side section 8. Of course, the lacings 7 and 10 will be loosened, and after the edges of the apparatus have been connected together as described the laces will be tightened to draw the apparatus about the figure and so modify the figure as desired. The necessary measurements for making a corset are then taken from the apparatus; and to facilitate in these measurements certain of the sections are provided with loops 16 through which may be threaded a tape measure or the like for taking the waist measurements, said loops indicating the line at which the waist measurements should be taken. Similarly certain of the sections have other loops 17 to indicate the line for taking the hip measurements. With a tape measure or the like threaded through the loops 16 and 17 horizontal lines are established from which other measurements may be taken.

Where it is desired that the corset have an abdominal support, the apparatus may be provided with a part 18 formed of three sections connected by lacings 19 as indicated by dotted lines on Figure 2, said part being arranged on the inside of the apparatus and adjustably connected thereto by straps 20 and buckles 21. The lacings 19 admit of the desired fit of the abdominal support, while the straps 20 and buckles 21 admit of different types or sizes of supports to be applied to the apparatus, as well as enabling the location of the support with respect to the side sections of the apparatus to be adjusted.

Instead of providing a plurality or series of front sections and a series of back sections, I may provide one front section and one back section having a plurality of series of fastener elements as shown in Figure 6 of the drawings. Here the front section 27 has at its edges three series of eyelets 23 arranged in spaced relation and with any of which series the hooks 12 at the edges of the side sections may be connected. Similarly the back section 28 is provided at each edge with a plurality of series of eyes 24 with which may be connected the hooks 13 at the corresponding edges of the side sections. With this construction it will be observed that the size or length of the apparatus may be modified as desired by connecting the hooks of the side sections to one or other series of eyes 23 or 24 on the front sections and back sections respectively. The use of this apparatus is otherwise identical with that of the apparatus shown in Figure 2.

While I have shown the invention as embodied in certain details of construction it will be understood that this is primarily for illustrating the principles of the invention

and that many modifications and changes may be made in the details of construction without departing from the spirit or scope of the invention.

Having thus described my invention, what I claim is:

A corsetiere's fitting apparatus comprising a front section, a back section and side sections, said sections extending from top to bottom of the apparatus, and each section being composed of a plurality of parts each extending from top to bottom of the respective section, means for connecting the side edges of said parts of each section for relative adjustment of said parts and quick-detachable fastener elements on both side edges of each of said sections to cooperate with the fastener elements on another section for separably connecting the side edges of said sections together so that a corsetiere may connect said sections together and apply said apparatus girthwise to the body of a person to be fitted for a corset, relatively adjust said parts of the sections by the first-mentioned means to modify the figure as desired, and take measurements for a corset to be made to maintain said modified figure.
